(57) CLAIM

The ornamental design for a table tennis table, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a table tennis table, embodying my new design according to a first embodiment;
FIG. 2 is a perspective view of a table tennis table, embodying my new design according to a second embodiment; and,
FIG. 3 is a perspective view of a table tennis table, embodying my new design according to a third embodiment.

The broken line showing in the photos shows subject matter that forms no part of the claimed design.

1 Claim, 3 Drawing Sheets
(3 of 3 Drawing Sheet(s) Filed in Color)
